(57) **CLAIM**

The ornamental design for wind turbine nacelle as shown and described.

DESCRIPTION

FIG. 1 is a front perspective view of the wind turbine nacelle;

FIG. 2 is a rear perspective view of the wind turbine nacelle;

FIG. 3 is a front view of the wind turbine nacelle;

FIG. 4 is a rear view of the wind turbine nacelle;

FIG. 5 is a top view of the wind turbine nacelle;

FIG. 6 is a bottom view of the wind turbine nacelle; and

FIG. 7 is a right side view of the wind turbine nacelle, the left side being a mirror image thereof.

FIG. 8 is a front perspective view of a second embodiment of the wind turbine nacelle that includes a fenced platform;

FIG. 9 is a rear perspective view of the second embodiment of the wind turbine nacelle;

FIG. 10 is a front view of the second embodiment of the wind turbine nacelle;

FIG. 11 is a rear view of the second embodiment of the wind turbine nacelle;

FIG. 12 is a top view of the second embodiment of the wind turbine nacelle;

FIG. 13 is a bottom view of the second embodiment of the wind turbine nacelle; and

FIG. 14 is a right side view of the second embodiment of the wind turbine nacelle, the left side being a mirror image thereof.
